Primary Examiner — Richard E Chilcot(57) **CLAIM**

The ornamental design for radio-controlled toy aircraft, as shown and described.

DESCRIPTION

1. Radio-controlled toy aircraft

1.1: Perspective

1.2: Perspective

1.3: Front

1.4: Back

1.5: Left

1.6: Right

1.7: Top

1.8 : Bottom

1 Claim, 8 Drawing Sheets(56)
